Patented June 20, 1922.

UNITED STATES PATENT OFFICE.

JOHN M. ROHRER, OF ORWIGSBURG, PENNSYLVANIA.

OIL CAN.

1,419,988.

Specification of Letters Patent. Patented June 20, 1922.

Application filed October 25, 1921. Serial No. 510,215.

To all whom it may concern:

Be it known that I, JOHN M. ROHRER, a citizen of the United States, residing at Orwigsburg, in the county of Schuylkill and State of Pennsylvania, have invented new and useful Improvements in Oil Cans, of which the following is a specification.

This invention relates to oil cans.

The object is to provide an oil can which is especially adapted for use in garages in applying lubricating oil in relatively large quantities to the crank casing of automobiles or for other similar uses, the can being so constructed as to obviate the necessity for using a funnel to direct the oil, and having means for controlling the flow thereof within easy reach of the hand of the operator.

Another object is to construct a can for this purpose which is easy to fill, and which will show the quantity of oil remaining in the same, the controlling means for the flow of the oil being readily removed from the can by simply removing a single clamping nut, when it is desired to renew the gaskets or washers necessary to prevent the leakage of the oil.

A full and complete understanding of the invention may be obtained from a consideration of the following detailed description taken in connection with the accompanying drawing forming a part of this specification; it being understood that while the drawing shows a practical form of the invention, the latter is not confined to strict conformity therewith, but may be changed or modified, so long as such changes or modifications mark no material departure from the salient features of the invention, as specifically pointed out in the appended claims.

In the drawing, in which similar reference characters designate corresponding parts throughout the several figures:

Figure 1 is an elevation, partly in section, of the improved oil can.

Figure 2 is an enlarged vertical sectional view through the controlling means.

Figure 3 is a front elevation of the supporting bracket for the controlling means.

The invention comprises an oil can or receptacle 1 formed of suitable sheet metal, having its upper end open and provided with a flaring rim 2, to which is attached a curved handle 3, which may be of any desired shape or construction. Surrounding the body of the can, at the proper heights from the bottom thereof, are a series of circumferential

indentations or beads 4, denoting the desired units of measure, such as pints, quarts, etc., or fractions thereof, depending upon the size of the can, the purpose of the same being to enable the operator to tell at a glance the amount of oil, or other liquid, still remaining in the receptacle. If desired, the order of these units may be reversed from top to bottom, as will be readily understood, so that the amount of liquid dispensed may be readily determined.

At one side of the can, and directly below one end of the handle 3 where attached to the flaring rim and adjacent to the bottom wall 5, is an aperture 6, which is adapted to receive the inner threaded end of a tubular spout 7, having its outer end 8 turned downwardly so as to direct the flow of oil or other liquid passing therethrough in a downward direction. Said tube passes through and is braced by a metallic strip 9, spaced from the outside of the can where surrounding the tube, and having a lateral bend 9a near its upper end to bring the latter against the side 80 of the can to which the same may be soldered, riveted or otherwise secured.

The threads on the inner end of the spout extend beyond the exterior of the can, and are adapted to receive a clamping nut 10 bearing against a rubber or leather gasket 11 surrounding the spout, and clamped by the nut against the adjacent side of the can. The threads of the tubular spout also engage a suitable threaded aperture formed in the long leg 12 of a supporting bracket 13, formed of a strip of metal bent intermediate of its length to provide an angularly disposed arm 14, whose terminal is curved as at 15 and having an open-ended slot 16 therein, as clearly shown in Figure 3 of the drawing. Interposed between the long leg 12 of the bracket and the interior of the wall of the can is a rubber or leather gasket 17, and it will be seen that when the nut 10 is tightened, the gaskets 11 and 17 are clamped in a manner to prevent any leakage of the contents of the can.

The bracket 13 is provided with a bracing wall 18, arranged at the longitudinal center line thereof, and suitably attached to the arms 12 and 14 of the bracket, the said wall providing means for pivoting a valve plate 19 thereto by means of a rivet 20, the said plate being provided with a bifurcation 21 to straddle the wall 18 and to be free to rock about the pivot thereof. At its lower end,

the valve plate 19 carries a rubber or leather gasket 22 of a size to fully cover the adjacent open end of the spout, and is held to the said plate by a screw 23 in order that the gasket 22 may be easily removed when desired to replace the same.

The valve plate furthermore carries an eye 24, to which is attached the lower end of an operating rod 25, arranged at an inclination and passing through the slot 16 in the end of the angular arm 14 of the bracket, and reaching above the top of the can or receptacle and traversing a suitable aperture in the handle 3, the upper end of the operating rod being formed into a ring 26, through which the finger of the operator may be introduced to pull the valve plate rearwardly and away from the open, inner end of the spout. A coiled, expansion spring 27 surrounds the rod 25, and has its ends bearing against the inner face of the valve plate and the under face of the arm 14, and tends to force the plate 19, together with the gasket 22, in closing relation to the end of the spout, the downwardly bent terminal of the arm 14 serving to prevent the spring or the rod from moving from their proper positions under the said arm 14.

From the foregoing it will be seen that a simple and inexpensive oil can has been provided, which is particularly adapted for use in applying lubricant to the crank case and other parts of automobiles, the spout 7 acting as a funnel to direct the flow of the oil, which may be readily controlled by means of the valve, the latter being readily operated from above to open or close the same at any time. Furthermore, when it is desired to replace any of the gaskets, the spout and the valve mechanism may be quickly detached from the can by simply removing the single nut 10.

What is claimed is:—

1. An oil can having an opening at one side near the bottom, a tubular spout having its inner end passed through the opening, means for securing the spout detachably in said opening, the inner end of the spout projecting beyond the inner wall of the can, a bracket detachably connected to the inner end of the spout, a valve plate pivoted to and carried by said bracket, a gasket at the lower end of the valve plate to seat itself on the inner end of the spout, and a spring-actuated rod connected to the valve plate and extending upwardly above the top of the can.

2. An oil can comprising a receptacle having a tubular spout threaded through the wall of the same near the bottom thereof, a bracket having angularly disposed arms disposed on the inside of the receptacle, one of the said arms having a threaded aperture to receive the inner end of the tubular spout, a nut carried on the spout exterior of the said wall, a gasket on the spout to provide a tight joint, a valve plate hingedly connected to the bracket between the arms thereof and adapted to hang pendently in covering relation to the end of the spout and carrying a gasket to impinge the same, an operating rod connected to the valve plate and guided by the free arm of the bracket and extending upwardly and beyond the top of the can, and a spring surrounding the rod and adapted to bear against the opposed faces of the free arm of the bracket and the valve plate to normally hold the latter against the end of the spout.

In testimony, that I claim the foregoing as my own, I have hereto affixed my signature.

JOHN M. ROHRER.
